CLAIM

The ornamental design for a cleaning tablet, as shown and described.

DESCRIPTION

FIG. 1 is a top perspective view showing the new design for a cleaning tablet;

FIG. 2 is a bottom perspective view thereof;

FIG. 3 is a top view thereof;

FIG. 4 is a bottom view thereof;

FIG. 5 is a right view thereof;

FIG. 6 is a left view thereof;

FIG. 7 is a back view thereof; and,

FIG. 8 is a front view thereof

The portions of the cleaning tablet with Surface Pattern in FIGS. 1–8 shown in broken lines are included to show features that form no part of the claimed design.

1 Claim, 6 Drawing Sheets
